(57) **CLAIM**

The ornamental design for an animal chew, as shown and described.

DESCRIPTION

FIG. 1 is a front, top and right side perspective view of a first embodiment of an animal chew in accordance with our new design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a front, top and right side perspective view of a second embodiment of an animal chew in accordance with our new design;

FIG. 9 is a front elevation view thereof;

FIG. 10 is a back elevation view thereof;

FIG. 11 is a right side elevation view thereof;

FIG. 12 is a left side elevation view thereof;

FIG. 13 is a top plan view thereof; and,

FIG. 14 is a bottom plan view thereof.

The broken lines shown in FIGS. 8-10 illustrate portions of the animal chew that form no part of the claimed design.

1 Claim, 6 Drawing Sheets
